UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

RADIATOR

Application filed October 26, 1931. Serial No. 571,114.

The invention relates to improvements in radiators and has among its principal objects the provision of a radiator comprised of a member having a plurality of fluid passages formed integral therewith to provide means for heating by radiation and to associate a heater element with said member, the latter being in communication with the fluid passages of said member to thereby provide means of the latter for heating by convection.

It is also an object of the invention to provide a heater comprised of means for heating by radiation and convection, said means being connected in series with each other so that the heating fluid is compelled to circulate from one to the other prior to its discharge therefrom to the return pipe of a heating system.

It is a further object of the invention to produce a structure having the above mentioned characteristics which is capable of being associated with a casing or a recess provided in a wall of a building to thereby provide one wall of the recess or casing, the member having the means for heating by radiation and convection being arranged relatively to the casing so that air passages are provided at the opposite ends of said member to thereby provide for circulation of air into and out of the recess or casing.

It is an object of the invention to construct the member having said plurality of fluid passages with means for controlling the flow of heating medium through said passages and to arrange a means for manipulating said controlling means so that said manipulating means is accessible from the outside of the casing or recess, one wall of which is formed by said device.

The invention has these and other objects, all of which will be explained and more readily understood when read in conjunction with the accompanying drawings which illustrate one embodiment of which the invention is susceptible, it being manifest that changes and modifications may be resorted to without departing from the spirit of the appended claims forming a part hereof.

In the drawings:

Fig. 1 is a front elevation of a radiator

constructed in accordance with the invention;

Fig. 2 is a section taken on line 2—2 of Fig. 1;

Fig. 3 is a section taken on line 3—3 of Fig. 2;

Fig. 4 is a section taken on line 4—4 of Fig. 3; and

Fig. 5 is a section taken on line 5—5 of Fig. 3.

The structure disclosed in the drawings for accomplishing certain of the various objects of the invention such as heating by radiation contemplates the utilization of a plate-like member 10 having fluid passages 11 and 12 and transverse passages such as 13—13 connecting the passages 11 and 12 which are formed integral with the plate-like member 10. The fluid passage 11 communicates with the passage 12 through the medium of the transverse passages 13 and since the plate with these passages formed therein is a single casting, this arrangement provides a means for heating by radiation, it being understood that the passage 11 has an opening such as 14 provided therein which is adapted to be connected with a fluid supply pipe 15 of a heating system.

It may be here stated that in the present disclosure the passage 11 is provided with a tubular extension 16 which is threaded as 17 for effecting a connection between the passages such as 11, 12 and 13 and the fluid supply pipe to thus supply fluid to said passages and another element connected with these passages which provides means for heating by convection and is generally designated 18. The tubular extension 16 also provides the body 19 of a valve generally designated 20 and thus will reduce the number of fittings necessary to be employed to connect the device with the heating system. The stem 21 of the valve is arranged so that it is accessible for manipulation from the outside of the casing to control the flow of heating fluid through the device when said plate-like member 10 and its associated elements are arranged to provide a wall of a recess or casing as hereinbefore referred to.

The passage 12 of the plate 10 is provided

with a threaded extension 22 which is adapted to receive a nipple 23, thereby providing a connection between the passages 11, 12 and 13 and the device generally designated 18 for heating by convection. The device generally designated 18 in the present instance is connected in series with the fluid passages 11, 12 and 13 and comprises a casting such as 24, one end of which is connected with the tubular passage 12 through the agency of the nipple 23. The opposite end such as 25 of the casting 24 is adapted to be connected with the return pipe of a heating system. The casting 24 has a wall 26 which divides the casting 24 into separate sections or chambers to thereby compel fluid circulating from the passages 11, 12 and 13 to the casting 24 to circulate from one of the chambers such as 27 formed by the wall through the U-shaped tubular branches 28 and 29 and thence to a chamber 30 from which it is discharged from the casting to the return pipe of the heating system. The U-shaped branches 28 and 29 of the heater generally designated 18 are provided with a plurality of heat radiating fins such as 31, the fins being disposed relatively to each other to provide spaces such as 32, the latter of which provide air passages and allow air to circulate between said fins and to engage with the U-shaped tubes such as 28 and 29 to thus heat by convection.

It will be noted that the structure thus far explained which involves the use of a plate such as 10 having the passages hereinbefore referred to and having the heater element 18 connected therewith provides a structure which will permit expansion and contraction of the plate-like member 10 without transmitting these strains to the tubes of the heater element 18 which will thus eliminate the possibility of cracking or breaking of joints and consequent leakage between the parts of the structure.

From an inspection of Fig. 2, it will be evident that the member 10 which provides the element for heating by radiation will, when associated with a recess provided in a wall of a building or with a casing such as that generally designated 33 provides one wall of the casing with a heating device such as 18 extending into the casing which will arrange the element 18 in the path of travel of air entering the recess to thus heat by convection. To provide for circulation of air through the casing the lower edge of the plate such as 10 is spaced a suitable distance from one end of the casing which provides an opening 34 to allow air to enter the casing, engage the tubes such as 28 and 29 of the heater generally designated 18 and also the fins thereof, heat said air and cause it to travel in an upward direction and out of the casing through the opening 35 which may be produced by arranging one edge of the plate 10 in spaced relation to one end of the casing or recess.

It may be here stated that the valve for controlling the flow of the heating medium through the device may be of any desired character, that is to say, it may be of the type shown or be of the "packless" variety such as 70 now found on the market.

From the foregoing description of the device, it is evident that a simple arrangement is provided which produces a unitary structure having means for heating by radiation 75 and means for heating by convection, the former comprising a plate having a plurality of tubular passages formed integral therewith and the latter being formed by a device including fluid passages having fins and spaces 80 provided between the fins to allow air to pass therebetween and be heated to thus heat air by convection, the structure allowing for the expansion and contraction of the elements without fear of breakage or leakage of the 85 parts entering into this construction. It is further evident from the foregoing that by providing the element 10 with a valve operable from the outside of the casing that this lends to simplicity of the device and facilitates installation. 90

Having thus described the invention, what I claim as new and desire to cover by Letters Patent is:

1. A radiator comprising a member having 95 a plurality of communicating passages formed therein, means for connecting said passages with a fluid supply pipe of a heating system thereby providing means for heating air by radiation, in combination with a 100 heating element associated with said member and having a passage connected with the passages of said member, means for connecting the passage of said element to the return of said heating system thereby providing means 105 connected with said member for heating by convection.

2. A radiator comprising a sheet of material having a plurality of fluid passages formed therein, the passages being connected with each other by said sheet material and having a heater element combined therewith communicating with said fluid passages and disposed along one edge and extending 110 from one face of said sheet. 115

3. A radiator comprising a sheet of material having a plurality of fluid passages formed integral and having a heater element combined therewith communicating with said fluid passages and disposed along one 120 edge and extending from one face of the sheet, and a valve for controlling the passage of fluid through said fluid passages of said plate. 125

4. A radiator comprising a sheet of material having a plurality of fluid passages formed integral and having a heater element combined therewith communicating with said fluid passages and disposed along one 130 edge and extending from one face of the

sheet, and a valve supported by the sheet controlling flow of fluid through the passages of said sheet.

5. A radiator comprising a plate having a plurality of fluid passages formed integral and having a heater element combined therewith communicating with said fluid passages and disposed along one edge and extending from one face of the plate, said plate being 10 provided with a valve body for a valve to control flow of fluid through said passages.

6. A radiator comprising a plate having a plurality of connected fluid passages formed integral with the plate, a heater element arranged upon one side of said plate, said heater element being connected with said passages and having a connection with the return of a heating fluid supply system.

7. A radiator comprising a member having a plurality of connected passages formed integral with said member, means for controlling the flow of a heating medium through said passages and a heater element connected with said passages, said heater element having fluid passages one of which is connected with the fluid passages of the plate and said heater element having a passage which communicates with a return passage of a heating system.

30 8. A radiator comprising a member having a plurality of connected passages formed integral with said member, means for controlling the flow of a heating medium through said passages and a heater element 35 connected with said passages, said heater element having fluid passages one of which is connected with the fluid passages of the plate and said heater element having a passage which communicates with a return passage 40 of a heating system, and said heater element having heat radiating fins arranged relatively to each other to provide air passages between said fins.

9. A radiator comprising a member having 45 a plurality of connected fluid passages formed integral with said member and having a fluid inlet and a fluid outlet, a heater element connected with said outlet, said heater having tubular elements which communicate with 50 and extend in opposite directions from said outlet longitudinally of an edge of said plate, one end of said tubular elements being adapted to be connected with a return of a heating system.

55 10. A radiator comprising a member having a plurality of connected fluid passages formed integral with said member and having a fluid inlet and a fluid outlet, a heater 60 element comprised of U-shaped tubular members extending in opposite directions relatively to the outlet of said first mentioned passages, one end of each of said tubular members being connected with said outlet and the opposite ends of said tubular members

being adapted to be connected with the return of a heating system.

11. A radiator comprising a member having a plurality of connected fluid passages formed integral with said member and having a fluid inlet and a fluid outlet, a heater element comprised of U-shaped tubular members 70 extending in opposite directions relatively to the outlet of said first mentioned passages, one end of each of said tubular members being connected with said outlet and the opposite ends of said tubular members being adapted to be connected with the return of a heating system, and heat radiating fins mounted upon said tubular elements 75 and arranged in spaced relation to each other to provide air passages between said fins.

12. A radiator comprising a sheet of material having a plurality of connecting fluid passages formed therein and adapted to be connected with a fluid supply and a fluid return of a heating system, said sheet being formed with a valve body for a valve for controlling flow of fluid through said passages of the sheet.

85 13. A radiator comprising a sheet of material having a plurality of connected fluid passages formed therein and means adapted 90 to connect said passages to a fluid supply and a fluid return of a heating system, in combination with a valve body formed in said sheet and a valve cooperating with said valve body adapted to control the flow of fluid 95 through the passages in said sheet, and means extending through said sheet for operating said valve.

100 14. A member providing an element of a heat exchange device, said member comprising a sheet of material, the material being formed to provide a passage for fluid and having a valve body of a valve for controlling flow of fluid through said passage formed in said member.

105 In witness whereof, I hereunto subscribe by name this 23rd day of October A. D., 1931.

ARTHUR B. MODINE.
